[57] **CLAIM**

The ornamental design for a target board for beanbag throwing game, as shown and described.

DESCRIPTION

FIG. 1 is a perspective view of a target board for beanbag throwing game showing our new design;

FIG. 2 is a top plan view thereof;

FIG. 3 is a front elevational view thereof;

FIG. 4 is a left side elevational view thereof; the right side elevational view being a mirror image thereof;

FIG. 5 is a bottom plan view thereof;

FIG. 6 is a rear elevational view thereof; and,

FIG. 7 is a sectional view thereof; taken along line 7—7 of FIG. 3.

In particular the novel and distinctive features of the said design include a generally oblong body portion, perpendicular to a generally rectangular base, and having a plurality of generally oblong semi-circular apertures having generally perpendicular flat oblong elements which extend outward from the base of each aperture.
